UNITED STATES PATENT OFFICE

KAORU AKASHI, OF LOS ANGELES, CALIFORNIA

SURGICAL THERMOMETER

Application filed January 3, 1931. Serial No. 506,403.

This invention relates to a new and useful thermometer adapted for surgery, home use, or physician's use to ascertain temperatures of the human body.

5 Thermometers of this character are frequently shaken in use to settle or place the indicating content, either mercury, or alcohol, in normal position in the thermometer body. In shaking the thermometer, it may slip from 10 the fingers and be broken, other times, it may be shaken a number of times.

To facilitate the manipulation of the thermometer, I have provided a foldable handle therefor which may be turned to open position, and whereby the thermometer may be twirled by the fingers and given an oscillating motion to place the indicating elements in their normal position within the thermometer tube and for other purposes.

20 The objects are to provide a handle for surgical thermometers whereby to facilitate its use in determining temperatures, and whereby to place the indicating element in its normal operative position.

25 In the drawing, Figure 1 is a front elevation of a surgical thermometer having my improved folding handle mounted thereon. Fig. 2 is a side elevation of the thermometer. Fig. 3 is an enlarged detail view of the handle. Fig. 4 is an enlarged detail side view of the handle. Fig. 5 is a detail plan view of a blank before bending, which forms the attaching clamp. Fig. 6 is a detail view of the clamp member detached from the handle.

35 Referring in detail to the drawing, the thermometer 7 is of the usual construction and form adapted for physician's and surgeon's use, and is provided with a handle 8, preferably made of hexagonal rod, and mounted on pivot shaft 9, projecting from clamp member 10. The clamp is lined with a rubber lining 11, adapted to engage with the body of thermometer 7. Clamp member 10 has projections 12 embossed thereon and adapted to

engage with the handle member 8 in its open position.

In use, the handle is turned to operative position extending at a right angle with the thermometer body 7, and is frictionally held in operative position by engagement of projections 12 with the handle member 8. The handle is then grasped between the fingers of the operator and is rapidly twirled for a few seconds. Through this motion, the mercury 55 is placed in proper position within the thermometer tube. The thermometer is then used in the usual manner for taking temperatures. The handle serves in the manipulation of the thermometer. After use, the handle may be 60 folded to longitudinal position relative to the body, and the same may then be inserted in a suitable case or receptacle. The clamp, being frictionally held in engagement with the thermometer body, may be shifted to other 65 positions thereon which may be desirable.

I claim:

1. A surgical thermometer, comprising a thermometer body, a clamp member in frictional engagement with the body, a pivot 70 shaft projecting from the clamp member, a handle mounted on the pivot shaft, and projections on the clamp member serving to engage with and hold the handle in angular position relative to the thermometer body. 75

2. A surgical thermometer, comprising a thermometer body, a clamp member in frictional engagement with the thermometer body, a pivot shaft projecting from the clamp 80 member, a handle operatively mounted on the pivot shaft, a rubber liner for the clamp, and projections on the clamp engaging with the handle in its operative position.

3. A surgical thermometer, comprising a 85 temperature-indicating body, a clamp member in frictional engagement with the body, a pivot shaft projecting from the clamp member, a handle operatively mounted on the pivot shaft, and means for maintaining the 90

handle in an angular position relative to the body.

4. A surgical thermometer, comprising a temperature indicating body, a twirling handle operatively mounted relative to the body and turnable to an inoperative position, a clamp member carrying the handle and serving to secure the handle to the body, and projections on the clamp adapted to maintain the handle in its operative position.

In testimony whereof, I hereunto affix my signature.

KAORU AKASHI.
